UNITED STATES PATENT OFFICE.

WILLIAM H. HAMPSON, OF WATERTOWN, MASSACHUSETTS.

HANDHOLD FOR VEHICLES.

Application filed March 1, 1927. Serial No. 171,905.

This invention relates to improvements in hand holds for vehicles and has for its object to provide a device of the character mentioned embodying therein a counterweighted portion acting to normally hold the device in a raised position tipped toward the adjacent side of said vehicle where it will be out of the way when not in use.

It is still further an object of the invention to provide the device with a handle member of sanitary construction, rigidly secured in a pivoted arm and capable of being easily detached therefrom when necessary, said handle portion also being capable of being positioned in said arm so that the gripping portion thereof may extend either longitudinally of or transversely of the vehicle.

The invention consists in a hand hold for vehicles as set forth in the following specification and particularly as pointed out in the claims thereof.

Referring to the drawings:—

Figure 1 represents a front elevation of a hand hold embodying my invention.

Fig. 2 is a side elevation of the hand hold as viewed from the left of Fig. 1.

Fig. 3 is a detail transverse section taken on the line 3—3 of Fig. 1.

Like numerals refer to like parts throughout the several views of the drawings.

In the drawings, 5 represents a supporting rod which extends longitudinally of the vehicle and 6 is an arm pivotally mounted upon said rod and positioned between collars 7 and 8 which are rigidly fastened to said rod and adapted to prevent said arm from moving longitudinally thereon. The arm 6 may be constructed of any suitable material and has an ear 9 formed integral therewith and projecting laterally therefrom into a slot 10 provided in the collar 8, and when the arm 6 is located in its normal position as illustrated in Fig. 2, the ear 9 engages a stop 11 formed upon the collar 8, while another stop 12, also formed upon said collar 8, limits the rocking movement of said arm in the opposite direction when the hand hold is grasped by a passenger within the vehicle.

A counterweight portion 13 is formed integral with the arm 6, said portion being of sufficient weight to normally hold the hand hold in the position illustrated in Fig. 2 with the ear 9 and the arm 6 in engagement with the stop 11 of the collar 8 when the hand hold is not in use. Located at the lower extremity of the arm 6 is a clamp portion 14

which is formed to receive a handle member 15, the latter being securely fastened to said clamp portion by a clamping member 16.

The handle member 15 may be constructed of any suitable material and preferably has a highly polished surface which may be easily cleaned or sterilized, and said handle member is provided with a squared shank portion 17 which fits oppositely disposed correspondingly formed grooved portions provided in the clamp portion 14 of the arm 6 and the clamping member 16, thereby rendering it impossible for said handle member to be rotated in said arm. The handle member 15 has a head portion 18 formed integral therewith at its upper extremity, said head portion projecting into a recess 19 formed in the arm 6 and also has a shouldered portion 20 formed thereon, the latter engaging the under extremity of the clamp portion 14 of the arm 6 and undersurface of the clamping member 16, and said head 18 and shoulder 20 prevent a longitudinal movement of said handle within said arm.

If it is thought desirable that the handle member 15 shall be located as illustrated in the dotted line position in Fig. 2, the clamping member 16 is detached from the portion 14 of the arm 6 and said handle member is removed from said portion 14 and reinserted therein in the desired position.

When the device is not in use the arm 6 and handle member 15 are overbalanced by the weight of the portion 13 of said arm, at which time said arm and handle will be located in an inclined position as illustrated in Fig. 2. When in this position the hand hold will be pointing from the center of the vehicle outwardly toward the windows at the side thereof and raised to such a position that it will not interfere with people standing in the vehicle. When, however, the hand hold is grasped it may be rocked toward the center of the vehicle, this rocking movement being limited by the position of the stop 12. When the hand hold is released the device will return to its normal position.

The handle member 15 may be mounted within the arm 6 as illustrated in full lines in Fig. 1, or as in dotted lines in Fig. 2.

I claim:—

1. A hand hold of the character described comprising, in combination, a support, an arm pivotally mounted upon said support and provided with a counterweight portion

thereon, a rigid handle member mounted in said arm, and means to limit the rocking movement of said arm upon said support.

2. A hand hold of the character described comprising, in combination, a support, an arm pivotally mounted upon said support and provided with a counterweight portion thereon, a handle member rigidly mounted in said arm, and a collar fast to said support and co-operating with said arm to limit the rocking movement of the latter upon said support.

3. A hand hold of the character described comprising, in combination, a support, an arm pivotally mounted upon said support and provided with a counterweight portion thereon, a handle member provided with a squared portion thereon, and a clamp engaging said squared portion and adapted to hold said handle in different positions relatively to said arm.

4. A hand hold of the character described

comprising, in combination, a support, an arm pivotally mounted upon said support and provided with a counterweight portion thereon, a handle member rigidly mounted in said arm, and means to prevent a movement of said arm longitudinally of said support, said means also embodying therein means to limit the rocking movement of said arm upon said support.

5. A hand hold of the character described comprising, in combination, a support, an arm pivotally mounted upon said support and provided with a counterweight portion thereon, a handle member provided with a squared portion thereon, a clamp engaging said squared portion and adapted to hold said handle in different positions relatively to said arm, and means to limit the rocking movement of said arm upon said support.

In testimony whereof I have hereunto set my hand.

WILLIAM H. HAMPSON.
